AUTOMATIC PILOT FOR MOBILE CRAFT

Alan M. MacCallum, Plainfield, and Charles Russell, Englewood Cliffs, N. J., assignors to Bendix Aviation Corporation, Teterboro, N. J., a corporation of Delaware

Application May 19, 1948, Serial No. 28,028

9 Claims. (Cl. 318—28)

1

This invention relates to automatic pilot systems for mobile craft, and more particularly to a steering surface control for mobile craft operative in response to a direction device.

An object of our present invention is to provide a rudder control for a mobile craft responsive to direction signals in which a repeater station for the direction signals is provided and where the direction signals may be varied to provide a course selector for the craft.

A further object of our invention is to provide a rudder displacement signal in an automatic pilot system of the character indicated, which provides the necessary reverse rudder action as the craft is brought about onto the preset course to prevent overshooting of the course.

Another object of this invention is to provide a rudder control system of the character indicated in which the natural period and response of the craft to rudder actuation is compensated for by the inclusion of a time delay or rate circuit in the system to maintain the craft on its preset course.

Still another object of the present invention is to provide a rudder control system of the general character described in which a continuously operated motor is used for actuating the rudder, the direction of rudder displacement being controlled electromagnetically by the operation of the system to provide correct rudder displacement for maintaining the craft on its course.

Still a further object of our invention is to provide a rudder control system of the character described which shall consist of few parts, relatively inexpensive to manufacture, which shall be positive and automatic in its operation, have a large variety of applications, and yet be practical and efficient to a high degree in use.

Other objects of the invention will in part be obvious, and in part hereinafter pointed out.

Referring now to the single figure of the drawings in which one of the various possible illustrative embodiments of our invention is shown as a schematic wiring diagram, the numeral 10 designates a circuit interconnecting a source of compass signal voltage 11 with a rudder actuating means generally designated by the numeral 12. The source of compass signal voltage comprises an earth inductor type of element arranged and mounted below and parallel to, a magnetic compass so that the deflection of the compass needle will induce in the three-phase stator winding 15, a component of the earth's magnetic field. The rotor winding 14 is connected across a suitable source of alternating current 16 and

2

saturates the stator winding core (not shown). A voltage will be induced in the stator winding 15 which is dependent upon the magnetic deflection of the compass needle.

5 The induced voltages in the stator winding 15 are impressed on a course setter 20 herein shown as a potentiometer winding 21 having two diametrically opposed wiper contacts 22 adapted to be rotated by a knob 23. The potentiometer winding 21 is divided at three points 120 degrees apart, each of the three legs of the winding being connected across a phase of the stator 15 by the leads 25. The signal voltage appearing across each of the respective legs of the potentiometer winding 21 is of the second harmonic, as is well known in the art. The wiper contacts 22 of the course setter will pick up the vector sum of the voltages appearing in the legs of the potentiometer winding 21. This signal voltage appearing across the wiper contacts 22 is applied by the lead 26 and by a lead 27 through the series connected resistors 28 and 29 to the primary winding 30 of a transformer 31. The secondary winding 32 of the transformer is center-tapped to ground as at 33. The ends of the secondary winding are connected to the control grids 34 and 35 of the two tetrode sections making up the tube 36.

The tube 36 comprises two indirectly heated cathodes 37 and 38, two screen grids 39 and 40, the two control grids and two plates 41 and 42. 30 The two sections of the tube 36 are connected in parallel and form a phase discriminator circuit. The plate 41 of the upper section is connected by a lead 45 through a relay coil 46 to a power lead 47 of a suitable source of alternating current. 35 The plate 42 is also connected to the power supply 47 through a relay coil 48 by a lead 49. The frequency of the power supply 47 is double that of the power supply 16. The screen grids 39 and 40 are interconnected by a lead 51 to the power lead 47, while the cathodes 37 and 38 are suitably connected to a source of bias voltage (not shown).

40 The relay coil 46 has associated therewith a switch arm 53 adapted to engage a fixed contact 54 upon energization of the relay coil 46. The relay coil 48 is similarly provided with a switch arm 55 and a fixed contact 56. The switch arms 53 and 55 are electrically interconnected and connected by a lead 57 to one terminal of a source of potential 58. The fixed contact 54 of the relay 45 46 is connected by a lead 59 to one end of a solenoid coil 60, the other end of said coil being connected by a lead 61 to the other terminal of the power supply 58. The fixed contact 56 of the relay 48 is connected by a lead 62 to one end of a 50 55

second solenoid coil 63, the other end of said coil being connected to the power lead 61.

The phase discriminating circuit described will operate the rudder actuating mechanism 12 to turn the rudder in the proper direction in response to the signal voltages. It will be understood by those versed in the art, that at any given instant the plate 41 and plate 42 will be cut-of-phase 180 degrees. As the voltage on the plate 41 rises to a positive value, the voltage on plate 42 will fall to a negative value. The phase of the signal voltage impressed across the center-tapped secondary winding 32 of the transformer 31 will be dependent upon the angular position of the compass needle with respect to the three-phase winding 15. This signal voltage will also be an alternating potential so that while the signal on the grid 34 is increasing to a positive value, the potential on the grid 35 will be decreasing to a negative value. Dependent, therefore, on the phase of the plate voltage and the grid voltage at any given instant will determine which section of the tube 33 will operate. The conduction of the section of the tube including the plate 41 will energize the relay 46, while the conduction of the other section of the tube will energize the relay 48.

Energization of the relay 46 will attract the switch arm 53 to close the switch arm and the fixed contact 54. An energizing circuit will thus be completed for the solenoid 60. This circuit may be traced from the power lead 61 through the solenoid coil through the lead 59, the fixed contact 54 and switch arm 53 and thence through the power lead 57 through the other terminal of the source of power 58. The energization of the relay 48 by the lower section of the tube will close the switch arm 55 and the fixed contact 56 to complete a similar circuit for the solenoid 63.

The solenoids 60 and 63 form a part of the rudder actuating mechanism 12. The rudder actuating mechanism comprises in addition, a continuously operating motor 65 operating through a differential mechanism 66 to actuate the rudder (not shown) through suitable gearing herein shown by the dashed line 67. The differential device 66 is provided with a braking mechanism 69 and 70 adapted to be actuated respectively by the solenoid 63 and 60.

For a more complete description of the differential mechanism 66 reference may be had to the copending application of Alan M. MacCallum for a Differential Servo with Continuously Running Motor filed on May 25, 1948, and bearing Serial No. 29,085, now abandoned. For a more detailed description of the braking mechanism 69 and 70, reference may be had to the copending application of Charles E. Gregory for a Balanced Brake Linkage bearing Serial No. 29,333 and filed on May 26, 1948.

The operation of the rudder actuating mechanism 12 is such that with the motor 65 operating and neither solenoid 60 or 63 energized, no output will be obtained from the differential mechanism 66. The rudder will, therefore, remain stationary in its neutral position. The development of a signal voltage across the leads 27 and 28 will operate either the solenoid 60 or 63 depending upon its phase. By the operation of either of the solenoids, the brake mechanism associated with the differential mechanism will be set by the energized solenoid to hold one half of the differential mechanism permitting the output thereof to be rotated in a given direction. The output of the differential 66 as applied to the rudder by

the gearing 67 will deflect the rudder in a direction responsive to the phase of the signal voltage.

Means is now provided to offset the signal voltage appearing across the leads 27 and 28 by a displacement signal voltage responsive to rudder position.

To this end there is provided a bridge potentiometer 75 having a continuous resistor 76 provided with two diametrically opposed wiper arms 77. The wiper arms 77 are adapted to be rotated through suitable gearing 78 upon operation of the differential mechanism in response to the signal voltages. Two diametrically opposite points 79 on the resistor wire 76 are connected by the leads 80 across the alternating power supply 47. The two wiper arms 77 are connected by the leads 81 across the resistor 28 in the output lead 27 of the course setter. The connection is so made that the signal of the bridge potentiometer is in opposition to the signal of the course setter. It will be noted in passing that when the rudder of the ship is in its neutral position, the wiper arms 77 will be in a position on the resistor winding which will equally divide the winding into four equal arms at which point no output voltage will be provided by the potentiometer across the resistor 28.

In the operation of the mechanism thus far described, the signal voltage provided by the course setter will operate the rudder in the manner described. The operation of the differential mechanism 66 in positioning the rudder will at the same time move the wiper arms 77 to provide an unbalanced condition of the bridge 75. This unbalanced condition of the bridge will provide a displacement signal which will oppose the signal voltage due to the compass signal. The two signals will tend to offset each other in anticipation of the craft coming about on the preset course. The energized solenoid will then become de-energized. The rudder displacement signal left in the circuit will reverse the operation of the differential mechanism 66 to provide a reverse rudder action to bring the rudder back to its neutral position.

The compass signals developed in the stator windings 15 are repeated in the three legs of the potentiometer 21 of the course setter. By rotating the knob 23 of the course setter, the wiper contacts 22 will be rotated over the potentiometer wire to provide a signal voltage which is dependent on the compass signal and the position of the wiper contacts. Thus, for a given course setting, the signal voltage appearing across the leads 26 and 27 will depend upon the heading of the craft. When the heading of the craft corresponds to the course set in, no signal voltage will appear across the leads 26 and 27 under normal conditions. The position of the compass needle with respect to the stator 15 and the position of the wiper contacts 22 with respect to the three legs of the potentiometer are such that no signal voltage will appear across the leads 26 and 27. With no signal voltage across the leads, both solenoids 60 and 63 will remain de-energized, the rudder being in its neutral position.

Upon craft deviation from the course set into the course setter 20, a condition of unbalance will exist which results in a signal voltage across the leads 26 and 27. Depending upon the direction of course deviation, the signal voltage will operate either the solenoid 60 or 63 in response to the phase of the signal voltage. The rudder will then be actuated to return the craft

to the preset course in the manner already described.

Due to the inertia of the ship and its slow response to rudder movement, the circuit thus far described will tend to overshoot the preset course on changes in course or large deviations from the preset course. A damping circuit based upon the natural period of the ship and its response to rudder actuation is provided and herein illustrated as a rate circuit generally designated by the numeral 100. The rate circuit comprises an input transformer 101 having a primary winding 102 connected by the leads 103 across the output leads 26 and 27 of the course setter 20. The secondary winding 103 of the transformer is center-tapped to ground and provides the input for a phase discriminator circuit 104 similar to that of the tube 36. The phase discriminator 104 comprises two triode sections 105 and 106, the output of which is connected to a time delay device 110. The time delay device 110 forms a part of a bridge circuit 112, the unbalance of which will provide a rate signal across the leads 113 which is then applied across the resistor 29 of the lead 27 in opposition to signal voltage. The time delay device comprises two resistors 115 and 116 in heat exchange relationship with two resistors 117 and 118, sealed in an envelope and connected into the plate circuits of the two sections 105 and 106. The bridge circuit 112 comprises the resistors 115 and 116 and the resistors 119 and 120. Potential is supplied to the bridge 112 by a transformer 121 connected across the power supply 47, the secondary winding of the transformer being connected across the resistors 115 and 120 and the resistors 116 and 119; the output being from the opposite diagonals via the leads 113.

The phase discriminating circuit comprising the tube 104 will take the signal voltage via the leads 103 and provide a plate current through the resistors 117 or 118 dependent upon the phase of the signal voltage. The plate current flowing through the resistor 117 or 118 will by heat exchange, change the value of the resistor 115 or 116 to unbalance the heretofor balanced bridge circuit 112. The signal voltage provided by the unbalance of the bridge circuit is applied by the leads 113 across the resistor 29 to oppose the signal voltage as developed by the course setter 20. The opposing voltage thus developed which is dependent upon the time of the displacement, or degree of deviation, will tend to anticipate the swing of the ship back to its course to provide the necessary reverse rudder action when required. By the addition of the rate circuit thus described, the ship will be kept on a true course as preset into the course setter regardless of the changes in course or degree of course deviation.

The resistor 29 is shown as a variable resistor so that the output voltage of the rate circuit may be varied. By changing the resistance value, different damping rates may be set into the system to compensate for a particular sailing or flight condition.

When the craft deviates a slight degree from the preset course, the bridge circuit 112 is ineffectual, since the signal voltage is of short duration and does not persist long enough to heat either of the bridge elements 115 or 116. Where, however, the course of the craft is changed by rotation of the control knob 23 or is off course a considerable degree due to weather

conditions, the rate circuit 100 will be effective to maintain the craft on the course as outlined. The rate circuit signal will also maintain the craft on the present course in conjunction with the signal voltages of leads 26, 27 and the feedback voltages appearing in leads 81 when cross-winds or quartering seas are encountered.

It will thus be seen that there is provided an automatic pilot for a mobile craft in which the several objects of this invention are achieved and which is well adapted to meet the conditions of practical use.

As various embodiments of the above invention might be made, and as various changes might be made in the embodiments above set forth, it will be understood that all matter herein set forth or illustrated in the accompanying drawing is to be interpreted as illustrative and not in a limiting sense.

Having thus described our invention, we claim as new and desire to secure by Letters Patent:

1. A steering system for mobile craft having a movable control surface thereon, comprising a motor adapted for operating said surface, direction responsive means for developing a signal when the craft departs from a prescribed course, course setter means having an input connected to said direction responsive means and an output for communicating a control signal to said motor, said motor responding to said control signal for displacing said surface to return said craft to said prescribed course, said course setter means being adapted for developing a course change signal at its output for operating said motor to displace said surface to change craft course, follow-up means operative during surface displacement for developing a follow-up signal for modifying operation of said motor, and means responsive to the signal of the output of said course setter means for deriving a damping signal therefrom for also controlling operation of said motor.

2. A steering system for mobile craft having a movable control surface thereon, comprising a motor adapted for operating said surface, direction responsive means for developing a signal when the craft departs from a prescribed course, course setter means having an input connected to said direction responsive means and an output for communicating a control signal to said motor, said motor responding to said control signal for displacing said surface to return said craft to said prescribed course, said course setter means being adapted for developing a course change signal at its output for operating said motor to displace said surface to change craft course, follow-up means operative during surface displacement for developing a follow-up signal for modifying operation of said motor, and means comprising a time delay device connected to the output of said course setter for deriving a further signal therefrom for further controlling operation of said motor.

3. A steering system for mobile craft having a movable control surface thereon, comprising a motor adapted for operating said surface, direction responsive means for developing a signal when the craft departs from a prescribed course, course setter means having an input connected to said direction responsive means and an output for communicating a control signal to said motor, said motor responding to said control signal for displacing said surface to return said craft to said prescribed course, said course setter means being adapted for developing a course change

signal at its output for operating said motor to displace said surface to change craft course, manually operable means for operating said course setter means to develop said course change signal, follow-up means operative during surface displacement for developing a follow-up signal for modifying operation of said motor, and time delay means connected to the output of said course setter for deriving a further signal therefrom for further controlling operation of said motor.

4. A steering system for mobile craft having a movable control surface thereon, comprising a motor adapted for operating said surface, direction responsive means for developing a signal when the craft departs from a prescribed course, course setter means comprising a potentiometer having an input connected to said direction responsive means and an output for communicating a control signal to said motor, said motor responding to said control signal for displacing said surface to return said craft to said prescribed course, said potentiometer being adapted for developing a course change signal at its output for operating said motor to displace said surface to change craft course, manually operable means for operating said potentiometer to develop said course change signal, follow-up means comprising a second potentiometer operative during surface displacement for developing a follow-up signal for modifying operation of said motor, and means connected to the output of said course setter means for deriving a further signal therefrom for further controlling operation of said motor.

5. A steering system for mobile craft having a movable control surface thereon, comprising a continuously operated motor adapted for operating said surface, means comprising a pair of solenoids adapted for selective energization determining the direction of displacement of said surface by said motor, a discriminator circuit for energizing one or the other of said solenoids depending upon the phase of an input signal applied thereto, direction responsive means for developing a signal when the craft departs from a prescribed course, course setter means having an input connected to said direction responsive means and having an output connected to the input of said discriminator circuit for operating said circuit in accordance with the signal of said direction responsive means whereby the surface is displaced to return the craft to said prescribed course, said course setter means being adapted for developing a course change signal at its output for displacing the surface to change craft course, follow-up means operative during surface displacement for developing a follow-up signal for modifying operation of said surface, and means connected to the output of said course setter means for deriving a further signal therefrom for further controlling operation of said surface.

6. A steering system for mobile craft having a movable control surface thereon, comprising a continuously operated motor adapted for operating said surface, means comprising a pair of solenoids adapted for selective energization determining the direction of displacement of said surface by said motor, a discriminator circuit for energizing one or the other of said solenoids depending upon the phase of an input signal applied thereto, direction responsive means for developing a signal when the craft departs from a prescribed course, course setter means comprising a potentiometer having an input connected to

10
said direction responsive means and having an output connected to the input of said discriminator circuit for operating said circuit in accordance with the signal of said direction responsive means whereby the surface is displaced to return the craft to said prescribed course, said potentiometer being adapted for developing a course change signal at its output for displacing the surface to change craft course, manually operable means for operating said potentiometer to develop said course change signal, follow-up means comprising a second potentiometer operative during surface displacement for developing a follow-up signal for modifying operation of said surface, and a damping circuit connected with the output of said course setter means for deriving a further signal to provide additional control of said surface.

7. A steering system for mobile craft having a
20 movable control surface thereon, comprising a
continuously operated motor adapted for oper-
ating said surface, means comprising a pair of
solenoids adapted for selective energization de-
termining the direction of displacement of said
25 surface by said motor, a discriminator circuit
for energizing one or the other of said solenoids
depending upon the phase of an input signal ap-
plied thereto, direction responsive means for de-
veloping a signal when the craft departs from a
30 prescribed course, course setter means compris-
ing a potentiometer having an input connected
to said direction responsive means and having
an output connected to the input of said dis-
criminator circuit for operating said circuit in
35 accordance with the signal of said direction re-
sponsive means whereby the surface is displaced
to return the craft to said prescribed course,
said potentiometer being adapted for developing
a course change signal at its output for displac-
40 ing the surface to change craft course, manu-
ally operable means for operating said poten-
tiometer to develop said course change signal,
follow-up means comprising a second poten-
tiometer operative during surface displacement
45 for developing a follow-up signal for modifying
operation of said surface, and means connected
to the output of said course setter means for de-
riving a further signal therefrom for further
controlling operation of the surface.

50 8. A steering system for mobile craft having
a movable control surface thereon, comprising a
motor adapted for operating said surface, atti-
tude change responsive means for developing a
first signal when the craft departs from a pre-
55 scribed position, a second signal developing de-
vice having a fixed part and a displaceable part,
said device having an input connected to said
attitude change responsive means and an output
at which a control signal is developed corre-
60 sponding to said first signal, a first electronic
device having an input connected with the out-
put of said signal developing device for receiv-
ing said control signal and an output connected
for operating said motor, manually operable
65 means for moving the displaceable part of said
second signal developing device for producing a
second control signal at its output to modify mo-
tor operation, and a second electronic device for
developing a damping signal for also controlling
70 operation of said motor, said second electronic
device having an input connected to receive at
least one of said control signals and an output
connected with the input of said first electronic
device.

75 9. A steering system for mobile craft having

a movable control surface thereon, comprising a motor adapted for operating said surface, attitude change responsive means for developing a first control signal when the craft departs from a prescribed position, an electronic device having an input connected to receive said signal and an output connected for operating said motor in accordance with said signal, a position change device for developing a second control signal for operating said motor and having an output connected to the input of said electronic device, and an electrical network for developing a damping signal for also controlling operation of said motor, said network having an input connected to receive at least one of said control signals and 15 an output connected with the input of said electronic device.
